UNITED STATES PATENT OFFICE.

MOSES FREUDENBERG, OF ST. PETERSBURG, RUSSIA.

KEY-WHEEL TYPE-WRITER.

1,095,099.

Specification of Letters Patent. Patented Apr. 28, 1914.

Application filed November 26, 1913. Serial No. 803,252.

To all whom it may concern:

Be it known that I, MOSES FREUDENBERG, a subject of the Emperor of Russia, and a resident of St. Petersburg, Russia, have invented a new and useful Improvement in Key-Wheel Type-Writers, of which the following is a specification.

My invention relates to typewriters of the key-wheel type and consists specifically in an improved form of platen and operating means therefor.

The object of the invention is to provide improved paper carrying and printing means, in which the paper is readily and accurately fed through the machine.

In the drawings, only those parts of a typewriter necessary to describe the improvement are shown.

Figure 1 is a side view of a typewriter of the key wheel type, fitted with my improvement; Fig. 2 is a top view of the same; and Fig. 3 is a perspective view of my improved form of platen.

1 represents my improved platen, which is roughly in the form of a rectangular frame. It is pivotally mounted by trunnions 2, which engage with recesses in the sides of the typewriter carriage. Joining the two lateral members of the platen frame 30 is a rod 3. This frame is made long enough to carry within it the feed rollers for the paper.

An elbow-lever 5, fulcrumed at 6, has provided a groove 4 at its upper end, in which rests the rod 3. The horizontal arm 7 of the lever 5 consists of a relatively long ledge 7. It is evident that downward pressure at any point along this ledge will depress it, move the vertical arm of the lever 5 to the right, and thus acting on rod 3 of the platen frame, move it to the right in the direction of the arrow 13.

The levers 8, fulcrumed at 9, rest on the ledge 7, and serve to transmit to said ledge impulses from the key lever 10; the key lever 10 is fulcrumed at 11 and may be provided with a retracting spring 12.

14 represents the key wheel of the usual type and actuated in the well-known way.

16 is a longitudinal feed roller, mounted in the carriage similarly to the platen frame 1. A sheet metal guide plate 15 for the paper is located as shown in Fig. 1, which is provided with slots, not shown, to permit the feed rollers 18 to contact with the

roller 16 and so grip the paper at several points.

17 represents a sheet of paper inserted ready for writing.

The platen frame 1, the feed rollers 16 and 18 and the guide plate 15, are all mounted on the carriage and move with it.

The impulses from the different keys are transmitted from various points along the ledge 7, the lever 5, thence to rod 3, whereupon the platen pushes the paper against the index wheel and so printing is effected. The long platen bar readily effects such printing, irrespective of at what point in its travel the carriage may be. At the same time, the long platen frame simplifies the passage of the paper through the machine.

I claim:

1. In a key wheel typewriter, the combination with a carriage, of a platen mounted thereon, of means for reciprocating said platen, comprising a bent lever, the upper arm of said lever carrying means for slidably engaging said platen, the lower arm of said lever consisting of a ledge, substantially parallel to the axis of travel of the carriage, a series of levers, one arm of each of said levers resting on said ledge, the other arm of each of said levers engaging with its individual key and adapted to be raised upon depression of said key.

2. In a key wheel typewriter, the combination with a carriage, of a platen on a substantially rectangular frame mounted on said carriage, feed rollers adapted to remain stationary during the reciprocation of said frame, and means for reciprocating said frame, upon depression of a key, comprising a bent lever pivoted to the body of the typewriter, the upper arm of said lever carrying means for slidably engaging said frame, the lower arm of said lever consisting of a relatively long ledge, substantially parallel to the line of travel of the carriage, a series of levers, pivoted to the body of the typewriter, one arm of each of said levers resting upon said ledge of said bent lever and adapted to depress said ledge, the other arm of each of said levers engaging with its individual key and adapted to be raised when said key is depressed.

3. In a key wheel typewriter, the combination with a series of keys, each pivoted between its ends, of a corresponding series of intermediate levers, each pivoted between

2

its ends and each engaging with its respective key lever, a bent lever, carrying an arm consisting of a relatively long ledge, said ledge adapted to engage each of said intermediate levers, a reciprocating platen, the second arm of said bent lever carrying means for slidingly engaging said platen.

In testimony whereof, I have signed my name to this specification in the presence of two subscribing witnesses.

MOSES FREUDENBERG.
